15 Claims. (Cl. 179—100.3)

1

This invention relates to the photographic recording of electrical impulses on a moving film as it is practiced, for example, in sound-on-film recording.

By such recording, two main kinds of photographic tracks may be produced on the moving film, namely, variable area tracks and variable density tracks. Among the means devised for their production, certain optical systems of the mirror oscillograph type lend themselves equally well to the production of both kinds of tracks. In these optical systems, a mirror mounted for vibration on an oscillograph galvanometer is employed for varying the light flux at the recording point, that is, the point at which the optical axis of the system strikes the film. The invention is concerned with optical systems of the mirror oscillograph type, and considers the production of both variable area and variable density tracks therewith.

More particularly, the invention is related to the production of variable area and variable density tracks which are composed of two half-tracks in juxtaposition. Each half-track is a complete record of the electrical impulses, but the two half-tracks are displaced 180° out of phase in relation to one another transversely of the film. This kind of track is known in the art as a push-pull class A track.

The advantages of push-pull class A tracks are well known, and hence need not be stated here anew. It is likewise known that, for the rest position of the oscillograph mirror, prints made of these tracks ordinarily have a comparatively wide transparent portion in the case of variable area tracks, and a comparatively large light transmission in the case of variable density tracks. This condition is unsatisfactory when the electrical impulses recorded in the tracks are sound currents so that sound is to be reproduced from the prints, for it then results in a comparatively large amount of ground noise. It is, of course, possible to employ, in the production of push-pull class A tracks, the well known electrical methods of ground noise reduction, be it the bias, or the shutter, method. But the application of either method presents certain difficulties and, in addition, requires special equipment such as rectifiers and the like.

The invention, therefore, proposes a method of, and means for, producing push-pull class A tracks in which ground noise reduction is inherent. Its starting point is the fact that the response of any conventional push-pull reproducing system is equal to the difference in response of the two

2

photocells employed therein. The individual responses of the photocells hence may be non-linearly related to the amplitude of the electrical impulses recorded in the push-pull class A tracks, as long as their difference is linearly related to that amplitude. Consequently, no amplitude distortion occurs when the push-pull class A tracks are so produced that the two component half-tracks of their prints have each a transparent portion, or light transmission, which is non-linearly related to the aforementioned amplitude if only the difference of the two transparent portions, or light transmissions, is linearly related thereto. Such a linear relationship is established, according to the invention, when the transparent portion, or light transmission, of each half-track on the print varies in proportion to the square of the amplitude referred to above. At the same time, a variation of this character brings it about that the value of the transparent portion, or light transmission, for the rest position of the oscillograph mirror decreases to such a degree that the ground noise is materially reduced when sound is reproduced from the print.

25 The invention, furthermore, provides the following method for recording push-pull class A tracks from which prints may be made with half-tracks having the properties outlined at the end of the preceding paragraph:

30 A film is moved vertically past the recording point at which two horizontal lines of light are produced in juxtaposition. The amount of light flux contained in each line of light is continuously varied in proportion to the square of the 35 amplitude of the electrical impulses to be recorded, but the amount of light flux contained in the one line of light is varied 180° out of phase in relation to the amount of light flux contained in the other line of light. When the variation 40 of the two amounts of light flux is accomplished by varying the length of the two lines of light, a variable area track is recorded, and when it is accomplished by varying their intensity, a variable density track is recorded.

45 The invention also proposes means for carrying out this method. In an optical system of the mirror oscillograph type, a screen is provided with a pair of uniformly illuminated openings, images of which are formed in the plane of a horizontal slit so as to be movable by the vibration of the oscillograph mirror. The two openings are substantially triangular and alike. They are spaced apart horizontally, and inversely positioned vertically in that the tip of the one opening is in alignment with the base of the other

opening, and vice versa. The shape of these openings is such that their effective horizontal extension or width, increases in proportion to the square of its distance from their tip. A variation in width of this character is obtained by providing each opening with one or two edges which extend from its tip towards its base, and whose effective contour is parabolic. The parabolic edges preferably have their vertex at the tip of the opening, and their axis parallel to its base. Since the edges are parabolic throughout their effective contour, the transition between any two points thereon is a smooth one. For that reason, and also because each opening continuously takes part in the variation of the light flux at the recording point, the use of a pair of these openings in the optical system introduces no higher order harmonic.

The ground noise reduction effected by the method and means of the present invention amounts to 3 decibels in the case of variable area tracks, and 6 decibels in the case of variable density tracks. These results are sufficient to make the application of the electrical methods of ground noise reduction superfluous in a great number of practical cases. The production of push-pull class A sound tracks with ground noise reduction hence is materially facilitated by the invention since its application requires neither special equipment, nor critical adjustment.

It should be noted that the terms "vertical" and "horizontal" have been used in the foregoing brief summary of the invention, and will be used throughout this specification, not in any absolute sense but merely as indicating two directions at right angles to each other, and that choice between these terms has been determined solely by convenience in description and illustration.

An object of the invention is the provision of improved push-pull class A tracks.

Another object of the invention is the provision of push-pull class A sound tracks with inherent ground noise reduction.

Another object of the invention is the provision of push-pull class A variable area tracks having half-tracks whose transparent portion varies in proportion to the square of the amplitude of the electrical impulses recorded in the tracks.

Another object of the invention is the provision of push-pull class A variable density tracks having half-tracks whose light transmission varies in proportion to the square of the amplitude of the electrical impulses recorded in the tracks.

Another object of the invention is to provide an improved method of producing push-pull class A tracks.

Another object of the invention is to provide a method of producing push-pull class A sound tracks with ground noise reduction which does not require special equipment.

Another object of the invention is the provision of improved means for producing push-pull class A sound tracks with inherent ground noise reduction.

Another object of the invention is the provision of such means which introduce no higher order harmonic.

Still other objects and advantages of the invention include those which are hereinafter stated or apparent, or which are incidental to the invention.

The invention will be better understood when the following description is considered with the accompanying drawings of certain presently pre-

fected embodiments thereof, and its scope will be pointed out in the appended claims.

In the drawings:

Fig. 1 is a diagrammatic perspective view of a variable area recording optical system in which the invention has been embodied.

Fig. 2 shows an enlarged elevation of a part of the optical system of Fig. 1, namely, a screen provided with a pair of openings according to the invention.

Fig. 3, which is drawn to a somewhat larger scale than Fig. 2, shows the openings of Fig. 2 related to a system of rectangular co-ordinates.

Fig. 4 is a diagrammatic representation of a print made from a push-pull class A variable area track produced by means of the openings of Fig. 2.

Figs. 5, 6, 7, and 8, show in enlarged elevation modifications of the openings which may be provided in the screen of Fig. 2.

Fig. 9, which is drawn to a somewhat larger scale than Fig. 8, shows the openings of Fig. 8 related to a system of rectangular co-ordinates.

Fig. 10 is a diagrammatic representation of a print made from a push-pull class A variable area track produced by means of the openings of Fig. 8.

Fig. 11 is a diagrammatic perspective view of a variable density recording optical system in which the invention has been embodied.

Fig. 12 is a diagrammatic longitudinal section of the optical system shown in Fig. 11, the optical axis being represented as a straight line and an oscillograph mirror as an aperture.

Fig. 13 is a corresponding section in the horizontal plane.

Fig. 14 is an enlarged front elevation of a part of the optical system of Fig. 11.

Fig. 15 is a diagrammatic representation of a print made from a push-pull class A variable density track produced by means of any of the pairs of openings shown in Figs. 2 and 5 to 8, and

Figs. 16 and 17 show adaptations to a particular purpose of the openings of Figs. 2 and 8, respectively.

Fig. 1 shows, by way of example, how the invention may be embodied in a conventional variable area recording optical system. The optical system of Fig. 1 has a suitable light source such as the filament 10 of an incandescent lamp 11. Lamp filament 10 is imaged substantially on the mirror 12 by the spherical condenser 13, and re-imaged substantially in the microscope objective 14 by the spherical lens 15.

A screen 20 is provided with two substantially triangular openings 21 and 22, and placed adjacent to condenser lens 13 so that openings 21 and 22 are uniformly illuminated by light flux from lamp filament 10. Openings 21 and 22, which are spaced apart horizontally, are alike but inversely positioned vertically in that the tip of the one opening is in alignment with the base of the other opening, and vice versa. The particular shape of openings 21 and 22 will be explained hereinafter.

A spherical lens 23 is placed in front of mirror 12 and forms on a screen 24 two images 25 and 26 of openings 21 and 22, respectively. Since openings 21 and 22 are uniformly illuminated, and since lens 23 is spherical, images 25 and 26 are two uniformly illuminated light spots whose shape and relative position are those of openings 21 and 22.

Screen 24 is placed adjacent to lens 15 and provided with a horizontal slit 27. Images 25 and

26 thus are formed in the plane of slit 27 so as to illuminate two portions thereof. As seen from the recording point 30, therefore, there appear at slit 27 two horizontal lines of light in juxtaposition which are reproduced at recording point 30 by the microscope objective 14. Recording point 30 is the point at which the optical axis of the system strikes the film 31, and film 31 moves at recording point 30 in a substantially vertical direction as indicated by the arrow 32.

Mirror 12 is mounted for vibration on an oscillograph galvanometer 33, or similar device for translating electrical impulses into mechanical vibrations. The axis 34-34 about which mirror 12 is adapted to vibrate, extends horizontally. When, therefore, the electrical impulses to be recorded are applied in known manner to the oscillograph 33, mirror 12 vibrates in accordance therewith and thereby moves images 25 and 26 vertically across the horizontal slit 27. This movement of images 25 and 26 brings it about that each of the two lines of light appearing at slit 27, and again at recording point 30, continuously varies in horizontal extension, or length, in accordance with the amplitude of the electrical impulses applied to oscillograph 33.

Thus, there is produced on film 31 as it moves vertically past recording point 30, a photographic record of the electrical impulses which are applied to the oscillograph 33. This record is made up of the two variable area tracks 35 and 36 in juxtaposition and, since the variation in length of the two lines of light at recording point 30 is continuous, each track 35 and 36 is a complete record of the electrical impulses. However, on account of the inverted position of openings 21 and 22, track 36 is displaced 180° out of phase in relation to track 35 transversely of film 31. Tracks 35 and 36 hence are the two component half-tracks of a push-pull class A variable area track 37. But track 37 is different from, and superior to, a conventional variable area track of the push-pull class A type for the following reasons.

Referring for the sake of further explanation to Fig. 2, there is shown an enlarged elevation of the screen 20 with the two substantially triangular openings 21 and 22. Opening 21 has two straight edges 40 and 41 which are at right angles to one another, and a curved edge 42 opposite the right angle formed by edges 40 and 41. Correspondingly, opening 22 has two straight edges 44 and 45 which are at right angles to one another, and a curved edge 46 opposite the right angle formed by edges 44 and 45. The particular manner in which edges 42 and 46 are curved, will be described presently.

Openings 21 and 22 are spaced apart horizontally so as to be separated by a distance $2d$, at which distance straight edge 40 of opening 21 and straight edge 44 of opening 22 are parallel to one another. Straight edges 41 and 45 of openings 21 and 22, respectively, are also parallel to one another, the distance between edges 41 and 45 being equal to the length $2h$ of edges 40 and 44. Assuming that straight edges 41 and 45 are the bases of openings 21 and 22, respectively, the tip V of opening 21 thus is in alignment with the base 45 of opening 22, while the tip W of opening 22 is in alignment with the base 41 of opening 21.

Curved edges 42 and 46, finally, are segments of two parabolae which are equal, but differently positioned. Edge 42 extends from tip V towards base 41 and is a segment of the parabola, opening to the right, which has its vertex at V and its

axis a parallel to base 41. Edge 46, on the other hand, extends from tip W towards base 45 and is a segment of the parabola, opening to the left, which has its vertex at W and its axis b parallel to base 45. Since the two parabolae are equal, and since edges 40 and 44 both are of the length $2h$, bases 41 and 45 are also of equal length (w).

Openings 21 and 22 thus are alike, but inversely positioned vertically in that the tip of the one opening is in alignment with the base of the other opening, and vice versa.

A specific property of openings 21 and 22 which results from their being bounded by parabolic edges 42 and 46, respectively, will now be explained with reference to Fig. 3. In this figure, which is drawn to a somewhat larger scale than Fig. 2, openings 21 and 22 are related to a system of rectangular co-ordinates $X-X$ and $Y-Y$. The origin O of this co-ordinate system is the center of the rectangle formed by the two straight edges 40 and 44, and the two extensions of bases 41 and 45, respectively, between edges 40 and 44. The axis $X-X$ of the system is parallel to bases 41 and 45, and its axis $Y-Y$ parallel to edges 40 and 44.

Since the length of edges 40 and 44 is $2h$ and that of the two extensions of bases 41 and 45 is $2d$, the co-ordinates of the tips V and W of openings 21 and 22, respectively, are (d, h) and $(-d, -h)$, respectively. Curved edge 42 thus is a segment of the parabola whose equation is

$$(1) \quad k(y-h)^2 = x-d$$

and curved edge 46 a segment of the parabola whose equation is

$$(2) \quad k(y+h)^2 = -(x+d)$$

In the above equations, k is a factor of proportionality whose choice governs the relation of the length w of bases 41 and 45 to the length $2h$ of edges 40 and 44.

Referring further to Fig. 3, a line l is drawn parallel to bases 41 and 45. Line l traverses openings 21 and 22 so that segments AB and CD are determined on it by edges 40 and 42 and edges 46 and 44, respectively. Fig. 3 also shows that, with respect to Equations 1 and 2, AB equals $x-d$ for a given value of y and CD equals $-(x+d)$ for the same value of y . According to

50 Equation 1, therefore,

$$AB = k(y-h)^2$$

and according to Equation 2,

$$CD = k(y+h)^2$$

55 so that

$$(3) \quad AB - CD = -4khy$$

The difference of the two segments AB and CD on one line l thus is a linear function of y , and this fact bears upon the operation of the optical system of Fig. 1 as follows:

As has been pointed out hereinabove, the images 25 and 26 formed in the plane of slit 27 are two uniformly illuminated light spots whose shape and relative position are those of openings 21 and 22. Furthermore, screen 20 is adjusted so that bases 41 and 45 of openings 21 and 22, respectively, extend horizontally, that is, in the same direction as mirror axis 34-34 and slit 27. For this adjustment of screen 20, line l of Fig. 3 indicates the horizontal line through openings 21 and 22 which is conjugate to slit 27 with respect to lens 23, the position of this line relative to bases 41 and 45 depending upon the angle of inclination of mirror 12. Segments AB and CD

on line 1, therefore, represent the two horizontal lines of light appearing at slit 27 and recording point 30 for a given angle of vibration of mirror 12. Moreover, the adjustment of mirror 12 is such that at its rest, or zero, position, that is, when no electrical impulses are applied to oscillograph 33, line 1 is halfway between bases 41 and 45 so as to coincide with axis X—X. The term y in Equations 1, 2, and 3, then denotes the deflection, by the vibration of mirror 12 about its axis 34—34, of images 25 and 26 with respect to slit 27 in such a manner that positive values of y indicate deflection upwards, that is, in a sense opposite to that indicated by the arrow 32, while negative values of y indicate deflection downwards, that is, in the sense indicated by arrow 32. According to Equations 1 and 2, the length of each of the two lines of light at slit 27 and recording point 30 thus varies in proportion to the square of the deflection of images 25 and 26, respectively, and the length of the one line varies at the same rate as, but 180° out of phase in relation to, the length of the other line. But, according to Equation 3, the difference in length of the two lines of light is a linear function of the deflection of images 25 and 26, and also of the amplitude of the electrical impulses applied to oscillograph 33 since the deflection of images 25 and 26 is proportional to this amplitude.

The two variable area half-tracks 35 and 36 on film 31, therefore, have modulated portions which are opaque and vary in this manner: The difference of their horizontal extensions, or widths, is a linear function of the amplitude of the electrical impulses applied to oscillograph 33, although their individual widths vary in proportion to the square of that amplitude; the width of the opaque portion of half-track 36 varying at the same rate as, but 180° out of phase in relation to, the width of the opaque portion of half-track 35.

The push-pull class A variable area track 37 which is composed of half-tracks 35 and 36, may be transferred from film 31 onto another film by printing. Such a print is illustrated, by way of example, in Fig. 4. A film 51 has printed thereon the push-pull class A variable area track 52 which is composed of the two half-tracks 53 and 54 in juxtaposition. Track 52 is shown, likewise by way of example, as being a record of the full cycle of a sine wave. This cycle is completely recorded on each half-track 53 and 54, but the two half-tracks are displaced 180° out of phase in relation to one another; the peak 55 on half-track 53 being opposite the valley 56 on half-track 54 transversely of film 51, and the valley 57 on half-track 53 being, in the same manner, opposite the peak 58 on half-track 54.

Each half-track 53 and 54 has an opaque portion 61 and 62, respectively, and a transparent portion 63 and 64, respectively. Transparent portions 63 and 64 are modulated portions of half-tracks 53 and 54, respectively. The horizontal extension, or width, of transparent portion 63 is w_1 , and that of transparent portion 64 is w_2 . As will readily be understood by those skilled in the art, w_1 and w_2 are related to the amplitude of the electrical impulses which were applied to the oscillograph 33, in the same manner as the widths of the opaque portions of half-tracks 35 and 36. That is to say, while w_1 and w_2 vary each in proportion to the square of that amplitude, the difference $w_1 - w_2$ is a linear function thereof. Since, furthermore w_1 and w_2 vary

180° out of phase in relation to one another, w_1 increases when w_2 decreases and vice versa.

Track 52 may be reproduced with any conventional push-pull reproducing system. Such a system essentially includes two photocells, one for each half-track, which generate voltages in a push-pull electrical circuit 180° out of phase. When track 52 is thus reproduced, a certain amount of light flux is transmitted by transparent portion 63 to the one photocell, and another amount of light flux by transparent portion 64 to the other photocell. Since these two amounts of light flux are linearly related to w_1 and w_2 , respectively, their difference is a linear function of the amplitude referred to above. So is the response of the entire reproducing system since it is, as is well known in the art, equal to the difference in response of the two photocells.

The electrical impulses applied to oscillograph 33, recorded on film 31, and printed onto film 51, may thus be reproduced without amplitude distortion although half-tracks 35 and 36, and half-tracks 53 and 54, are distorted because the width of their individual modulated portions varies in proportion to the square of the amplitude of said electrical impulses.

So far, it has been explained only that undistorted reproduction of the electrical impulses recorded with the optical system of Fig. 1 may be had despite the employment therein of two openings each of which is bounded by a parabolic edge. Now it will be shown wherein the advantage resides of employing such openings rather than the conventional openings which are bounded by three straight edges. Referring to that end again to Fig. 3, it has been pointed out hereinabove that mirror 12 is adjusted so that, when it is at rest, line 1 coincides with axis X—X. For this position of line 1, the segments AB and CD thereon become the segments A'B' and C'D' on axis X—X. The length of each segment A'B' and C'D' is kh^2 , which value is obtained by substituting 0 for y in Equations 1 and 2 and solving them for $x-d$ and $-x+d$, respectively. The difference in length of segments A'B' and C'D' hence equals zero—which result is also obtained by substituting 0 for y in Equation 3—and so does the difference $w_1 - w_2$ when the value of w_1 and w_2 each becomes equivalent to kh^2 . Thus, there actually is no response from half-tracks 53 and 54 when mirror 12 is at rest.

Furthermore, the length kh^2 of segments A'B' and C'D' is one quarter of the length w of bases 41 and 45 since w equals $4kh^2$. This result is obtained by substituting $-h$ for y in Equation 1 and $+h$ for y in Equation 2 and solving the two equations for $x-d$ and $-(x+d)$, respectively.

A broken line 48 is drawn from the tip V of opening 21 to the end point P of its base 41, and a broken line 49 from the tip W of opening 22 to the end point Q of its base 45. Lines 48 and 49 both are straight. There is determined, therefore, on axis X—X the segment A'E by edge 49 and line 48, and the segment FD' by line 49 and edge 44. According to elementary geometry, the length of segments A'E and FD' is half the length w of bases 41 and 45, that is, twice the length of segments A'B' and C'D'.

The fact that the length of segments A'B' and C'D' is

while the length of segments A'E and FD' is

$$\frac{w}{2}$$

leads to the following conclusions:

Let it be assumed that, in the optical system of Fig. 1, there are employed openings 21 and 22 and, alternatively, two conventional openings which are bounded by the straight edges 40, 41 and 48, and 44, 45 and 49, respectively. Since the two pairs of openings both have edges 41 and 45 as their bases, the maximum length which each of the two lines of light at slit 27 and recording point 30 may have, is the same in either case. But, when mirror 12 is at rest, the length of the two lines of light is half their maximum length with the two straight-edged openings, while it is reduced to one quarter of that length with openings 21 and 22. The opaque portions of half-tracks 35 and 36, and the transparent portions 63 and 64, therefore, may have the same maximum width with either pair of openings. But their width for the rest position of mirror 12 is half their maximum width with the conventional pair of openings, while it is reduced to a quarter of that width with the pair of openings according to the invention.

The variable area half-tracks 35 and 36, and 53 and 54, thus are characterized by the fact that their modulated portion has a width whose zero value, that is, the value for the rest position of mirror 12, is one quarter its maximum value, that is, the value for the maximum vibration of mirror 12. This relationship between the zero and maximum values of the width of transparent portions 63 and 64 becomes important when the electrical impulses applied to oscillograph 33 are sound currents so that sound is to be reproduced from track 52 on film 51. Its establishment then effects a reduction of ground noise which amounts to 3 decibels. This result is sufficient to make the application of the electrical methods of ground noise reduction superfluous in a great number of practical cases so that the production of variable area sound tracks with ground noise reduction is materially facilitated by the present invention.

As shown in Figs. 2 and 3, and described hereinabove, openings 21 and 22 are inversely positioned vertically in that the tip of the one opening is in alignment with the base of the other opening, and vice versa. As further shown in Figs. 2 and 3, openings 21 and 22 are inversely positioned also horizontally in that their straight edges 40 and 44 face each other, while their parabolic edges 42 and 46 are turned away from each other and open in opposite senses. In other words, openings 21 and 22 are arranged symmetrically with respect to the point at which the straight line through their tips V and W is intersected by the straight line through the end points P and Q of their bases 41 and 45, respectively. This point coincides with the origin O in Fig. 3.

However, the fact that openings 21 and 22 have a center of symmetry, is immaterial as far as the present invention is concerned. That is to say, the invention may be carried out also with pairs of openings which are inverted only vertically. Two such pairs of openings are shown in Figs. 5 and 6 by way of further example. Fig. 5 shows the opening 21 of Figs. 2 and 3 associated with an opening 72. The corresponding edges 40 and 84, 41 and 85, and 42 and 86, of openings 21 and 72 are of equal length, and the

tip V of opening 21 is in alignment with the base 85 of opening 72 whose tip W' in its turn, is in alignment with the base 41 of opening 21. Openings 21 and 72 thus are alike but inversely positioned vertically. More particularly, straight edges 40 and 41 of opening 21 form a right angle, and so do straight edges 84 and 85 of opening 72. Curved edge 42 of opening 21 is opposite the right angle formed by edges 40 and 41, and curved edge 86 of opening 72 is opposite the right angle formed by edges 84 and 85. The length of straight edges 40 and 84 is $2h$, that of straight edges 41 and 85 is w , and curved edges 42 and 86 are segments of two parabolae which are equal, but differently positioned. The parabola of edge 42, which opens to the right, has its vertex at V and its axis a parallel to base 41 so that edge 42 extends from tip V towards base 41. The parabola of edge 86 opens also to the right, but has its vertex at W' and its axis b' parallel to base 85 so that edge 86 extends from tip W' towards base 85.

Finally, openings 21 and 72 are spaced apart horizontally in such a manner that edges 40 and 84 are at the distance $2d+w$ parallel to one another, while the distance of tip V from base 85 is $2d$ and that of tip W' from base 41 is $2d+w$.

Openings 21 and 72 are related to a system of rectangular co-ordinates with axes X—X and Y—Y. Axis X—X is parallel to bases 41 and 85 and intersects edges 40 and 84 at their midpoints, and axis Y—Y is parallel to edges 40 and 84, its distance from these edges being d and $d+w$, respectively. The equation of parabolic edge 42 then is again

$$(1) \quad k(y-h)^2 = x - d$$

while the equation of parabolic edge 86 is

$$(4) \quad k(y+h)^2 = x + 4kh^2 + d$$

$4kh^2$ being equal to w as has been pointed out hereinabove. The difference, therefore, of the two segments determined on line l by edges 40 and 42, and edges 84 and 86, respectively, again equals $-4khy$ (Equation 3), and it again becomes zero when line l coincides with axis X—X. The length of the two segments is again kh^2 , or $w/4$ in radians

in this case, while

is again the length of the two segments determined on axis X—X by the sides of the two right-angled triangles whose cathetes are edges 40 and 41, and edges 84 and 85, respectively.

In Fig. 6, the opening 22 of Figs. 2 and 3 is associated with an opening 71. The corresponding edges 44 and 80, 45 and 81, and 46 and 82, of openings 22 and 71 are of equal length, and the tip W of opening 22 is in alignment with the base 81 of opening 71 whose tip V', in its turn, is in alignment with the base 45 of opening 22. Openings 22 and 71 thus are alike but inversely positioned vertically.

More particularly, straight edges 44 and 45 of opening 22 form a right angle, and so do straight edges 80 and 81 of opening 71. Curved edge 46 of opening 22 is opposite the right angle formed by edges 44 and 45, and curved edge 82 of opening 71 is opposite the right angle formed by edges 80 and 81. The length of straight edges 44 and 80 is $2h$, that of straight edges 45 and 81 is w , and curved edges 46 and 82 are segments

of two parabolae which are equal, but differently positioned. The parabola of edge 46, which opens to the left, has its vertex at W and its axis b parallel to base 45 so that edge 46 extends from tip W towards base 45. The parabola of edge 82 opens also to the left, but has its vertex at V' and its axis a' parallel to base 81 so that edge 82 extends from tip V' towards base 81. Finally, openings 22 and 71 are spaced apart horizontally in such a manner that edges 44 and 80 are at the distance $2d+w$ parallel to one another; while the distance of tip W from base 81 is $2d$ and that of tip V' from base 45 is $2d+w$.

Openings 22 and 71 are related to a system of rectangular co-ordinates with axes X—X and Y—Y. Axis X—X is parallel to bases 45 and 81 and intersects edges 44 and 80 at their midpoints, and axis Y—Y is parallel to edges 44 and 80, its distances from these edges being d and $d+w$, respectively. The equation of parabolic edge 46 then is again

$$(2) \quad k(y+h)^2 = -(x+d)$$

while the equation of parabolic edge 82 is

$$(5) \quad k(y-h)^2 = -(x-4kh^2-d)$$

wherein $4kh^2$ is equal to w . The difference, therefore, of the two segments determined on line l by edges 82 and 80, and edges 46 and 44, respectively, again equals $-4khy$ (Equation 3), and it again becomes zero when line l coincides with axis X—X. The length of the two segments is again kh^2 , or

$$\frac{w}{4}$$

in this case, while

$$\frac{w}{2}$$

is again the length of the two segments determined on axis X—X by the sides of the two right-angled triangles whose cathetes are edges 80 and 81, and edges 44 and 45, respectively.

Openings 72 and 71 which have been shown in Figs. 5 and 6 as associated with openings 21 and 22, respectively, may also be associated one with another as shown in Fig. 7. Openings 71 and 72 are alike, as will be seen from the description of Figs. 5 and 6, and arranged so that the tip V' of opening 71 is in alignment with the base 85 of opening 72 whose tip W', in its turn, is in alignment with the base 81 of opening 71. The two openings are spaced apart horizontally in such a manner that edges 80 and 84 are at the distance $2d+2w$ parallel to one another, while the distance of tips V' and W' from bases 85 and 81, respectively, is $2d+w$. Openings 71 and 72 thus are inversely positioned not only vertically, but also horizontally.

Openings 71 and 72 are related to a system of rectangular co-ordinates with axes X—X and Y—Y. Axis X—X is parallel to bases 81 and 85 and intersects edges 80 and 84 at their midpoints, and axis Y—Y is parallel to edges 80 and 84, its distance from either edge being $d+w$. Parabolic edges 82 and 86 then are again the lines conforming to Equations 4 and 5, respectively. The difference, therefore, of the two segments determined on line l by edges 82 and 80, and edges 84 and 86, respectively, again equals $-4khy$ (Equation 3), and it again becomes zero when line l coincides with axis X—X. The length of the two segments is again kh^2 , or

$$\frac{w}{4}$$

in this case, while

$$\frac{w}{2}$$

is again the length of the two segments determined on axis X—X by the sides of the two right-angled triangles whose cathetes are edges 80 and 81, and edges 84 and 85, respectively.

When the openings 21 and 72 of Fig. 5, the openings 22 and 71 of Fig. 6, or the openings 71 and 72 of Fig. 7, are in the screen 20 of the optical system of Fig. 1, screen 20 is adjusted so that bases 41 and 85, 45 and 81, or 81 and 85, extend horizontally. Also mirror 12 is adjusted so that, at its rest position, line l is halfway between bases 41 and 85, 45 and 81, or 81 and 85. The optical system of Fig. 1 then operates in the manner described hereinabove in connection with openings 21 and 22. In each of the cases illustrated in Figs. 5 to 7, therefore, the explanations are valid which have previously been made as regards the variation in length of the lines of light at slit 27 and recording point 30, and the variation in width of the opaque portions of half-tracks 35 and 36, and of the transparent portions 63 and 64.

More particularly, when a print is made of the push-pull class A variable area track produced on film 31 with any one of the pairs of openings shown in Figs. 5 to 7, the track thus obtained by printing has the general appearance of the track 52 illustrated in Fig. 4. The track on such a print hence is again composed of the two variable area half-tracks 53 and 54 which are complete but displaced 180° out of phase in relation to one another, and each of the two transparent portions 63 and 64 has again a width whose zero value is one quarter its maximum value.

The only difference between the tracks produced by means of the various pairs of openings 40 is in the relative position of the straight boundaries of the opaque portions of half-tracks 35 and 36, and of transparent portions 63 and 64. In the case of openings 21 and 22, the straight boundaries of transparent portions 63 and 64 coincide with the inner boundaries 67 and 68, respectively, of half-tracks 53 and 54, as illustrated in Fig. 4. With openings 21 and 72, the straight boundary of portion 63 retains its position, while that of portion 64 coincides with the outer boundary 70 of half-track 54. With openings 22 and 71, the straight boundary of portion 64 has the position illustrated in Fig. 4, while that of portion 63 coincides with the outer boundary 69 of half-track 53. With openings 71 and 72, finally, the straight boundaries of portions 63 and 64 coincide with outer boundaries 69 and 70, respectively.

The straight boundaries of the opaque portions of half-tracks 35 and 36 correspondingly change their position since it, too, depends upon the difference in position, relative to each other, of vertical edges 40 and 44, 40 and 84, 44 and 80, and 80 and 84, as illustrated in Figs. 2 and 5 to 7.

The openings shown in Figs. 2 and 5 to 7 all have a shape which is derived from a right triangle. When, therefore, these openings are in the screen 20 of the optical system of Fig. 1, the half-tracks 35 and 36 on film 31, and the half-tracks 53 and 54 on film 51, are unilateral variable area tracks as illustrated in Figs. 1 and 4. The invention, however, may also be employed when it is desired that the push-pull class A tracks on films 31 and 51, respectively, be composed of two variable area half-tracks of the bilateral, or symmetrical, type. To achieve this end, there must be employed in screen 20 two

13.

openings whose shape is derived from an isosceles triangle, such as the openings 90 and 94 shown in Fig. 8 by way of example.

Opening 90 has a straight edge 91 and is symmetrical with respect to the line RV₁ which is perpendicular to edge 91 at its midpoint R. The curved edges 92 and 93 of opening 90 extend from V₁ towards edge 91 and are segments of two equal parabolae whose vertices are at V₁, and whose axes a₁ and a₂, respectively, are parallel to edge 91. The two parabolae, however, open in opposite senses, the parabola of edge 92 opening to the right and that of edge 93 to the left.

Similarly, opening 94 has a straight edge 95 and is symmetrical with respect to the line SW₁ which is perpendicular to edge 95 at its midpoint S. The curved edges 96 and 97 of opening 94 extend from W₁ towards edge 95 and are segments of two parabolae which are equal to one another, and also to the parabolae of edges 92 and 93. The parabolae of edges 96 and 97 have their vertices at W₁ and their axes b₁ and b₂, respectively, parallel to edge 95. They open, however, in opposite senses, the parabola of edge 96 opening to the left and that of edge 97 to the right.

The distance of the tips V₁ and W₁ from the bases 91 and 95 of openings 90 and 94, respectively, is 2h. Since, furthermore, the four parabolae whose vertices are at V₁ and W₁ respectively, are equal, bases 91 and 95 are of equal length (w). Openings 90 and 94, which thus are alike, are arranged so that the tip V₁ of opening 90 is in alignment with the base 95 of opening 94 whose tip W₁, in its turn, is in alignment with the base 91 of opening 90. The two openings are spaced apart horizontally in such a manner that bases 91 and 95 are at the distance 2h parallel to one another, and that the distance of tips V₁ and W₁ from bases 95 and 91, respectively, is

$$2d + \frac{w}{2}$$

Openings 90 and 94 hence are inversely positioned vertically.

In Fig. 9, which is drawn to a somewhat larger scale than Fig. 8, openings 90 and 94 are related to a system of rectangular co-ordinates with axes X—X and Y—Y. Axis X—X is parallel to bases 91 and 95 so as to intersect the two normals RV₁ and SW₁ at their midpoints G and H, respectively, and axis Y—Y is parallel to the normals RV₁ and SW₁ so that its distance from either normal is

$$d + \frac{w}{2}$$

The co-ordinates of tips V₁ and W₁ then are

$$\left(d + \frac{w}{2}, h\right) \text{ and } \left[-\left(d + \frac{w}{2}\right), -h\right]$$

respectively, or $(d + 2kh^2, h)$ and

$$[-(d + 2kh^2), -h]$$

respectively. This substitution of $2kh^2$ for

$$\frac{w}{2}$$

is based on the assumption that w in the case of openings 90 and 94 equals w in the case of openings 21 and 22, and in the latter case w is equal to $4kh^2$ as has been shown hereinabove.

A comparison of Figs. 8 and 9 with Figs. 2 and 3, furthermore, reveals that the normals RV₁ and SW₁ and the straight edges 40 and 44 have the same length (2h) and are the tangents at the vertex of the respective parabolae in each case.

14.

But the distance of parabolic edges 92 and 93 from the normal RV₁, and that of parabolic edges 96 and 97 from the normal SW₁, is

$$\frac{w}{2}$$

at bases 91 and 95, respectively, while the distance of parabolic edge 42 from straight edge 40, and that of parabolic edge 46 from straight edge 44, is w at bases 41 and 45, respectively. This condition makes it necessary to reduce the factor of proportionality k in Equations 1 and 2 by one half in the equations for parabolic edges 92, 93, 96, and 97.

The equation of parabolic edge 92 thus is

$$(6) \quad \frac{k}{2}(y-h)^2 = x - 2kh^2 - d$$

that of parabolic edge 93

$$(7) \quad \frac{k}{2}(y-h)^2 = -(x - 2kh^2 - d)$$

that of parabolic edge 96

$$(8) \quad \frac{k}{2}(y+h)^2 = -(x + 2kh^2 + d)$$

and that of parabolic edge 97

$$(9) \quad \frac{k}{2}(y+h)^2 = x + 2kh^2 + d$$

Referring further to Fig. 9, the line l is drawn parallel to bases 91 and 95. Line l traverses openings 90 and 94 so that there are determined on it again the two segments AB and CD, this time, however, by the curved edges 93 and 92, and 96 and 97, respectively. Segment AB is divided by the normal RV₁ into the two equal segments AK and KB, and segment CD is divided by the normal SW₁ into the two equal segments CL and LD. Fig. 9 also shows that, for the same value of y, segments AK, KB, CL, and LD, are equal to the right members of Equations 7, 6, 8, and 9, respectively. According to Equation 7, therefore,

$$AK = \frac{k}{2}(y-h)^2$$

and, according to Equation 6,

$$KB = \frac{k}{2}(y-h)^2$$

so that

$$AB = AK + KB = k(y-h)^2$$

Furthermore, according to Equation 8,

$$CL = \frac{k}{2}(y+h)^2$$

and, according to Equation 9,

$$LD = \frac{k}{2}(y+h)^2$$

so that

$$CD = CL + LD = k(y+h)^2$$

The difference of the two segments AB and CD on line l hence is again a linear function of y since again

$$(3) \quad AB - CD = -4kh^2$$

When, in the case of Fig. 9, line l coincides with axis X—X, segments AB and CD become segments A'B' and C'D', respectively, as in the case of Fig. 3. But segment A'B' now is composed of the two equal segments A'G and GB', and segment C'D' of the two equal segments C'H'

15

and HD' . The length of each segment $A'G$, GB' , $C'H$, and HD' , is

$$\frac{kh^2}{2}$$

which value is obtained by substituting O for y in Equations 6 to 9 and solving them for their right members. The length of segments $A'B'$ and $C'D'$ thus is again kh^2 , or

$$\frac{w}{4}$$

that is, half the length of the two segments ME and FN which are determined on axis $X-X$ by the sides of the two isosceles triangles with bases 91 and 95 , and tips V_1 and W_1 , respectively.

When openings 90 and 94 are in the screen 20 of the optical system of Fig. 1, screen 20 is adjusted so that bases 91 and 95 extend horizontally, and the adjustment of mirror 12 is such that, at its rest position, line l is halfway between bases 91 and 95 . The push-pull class A track produced on film 31 then is composed of two variable area half-tracks each of which is symmetrical about its vertical center line. Apart from their symmetry, however, these two half-tracks have the same characteristics as the unilateral half-tracks 35 and 36 . That is to say, the horizontal extension, or width, of the individual opaque portions of the two symmetrical half-tracks varies in proportion to the square of the amplitude of the electrical impulses applied to oscilloscope 33 , but the difference in width of the two opaque portions is a linear function of that amplitude. Also, the zero value of this width is one quarter its maximum value since the length of segments $A'B'$ and $C'D'$ is one quarter the length w of bases 91 and 95 .

When the push-pull class A symmetrical variable area track produced on film 31 by means of openings 90 and 94 is transferred onto film 51 by printing, the resultant print has the general appearance of the track 102 shown in Fig. 10. Like track 52 , track 102 is illustrated as being a record of the full cycle of a sine wave. This cycle is completely recorded on each of the two half-tracks 103 and 104 which compose track 102 , but half-tracks 103 and 104 are displaced 180° out of phase in relation to one another transversely of film 51 . Half-tracks 103 and 104 thus are displaced in the same manner as half-tracks 53 and 54 of Fig. 4.

Half-track 103 is symmetrical about its vertical center line $105-105$, and has a transparent portion 106 which divides its opaque portion into the two portions $107a$ and $107b$. Correspondingly, half-track 104 is symmetrical about its vertical center line $108-108$, and has a transparent portion 109 which divides its opaque portion into the two portions $110a$ and $110b$. Finally, the widths w_1 and

$$\frac{w}{2}$$

of transparent portions 106 and 109 , respectively, vary each in proportion to the square of the amplitude of the electrical impulses applied to oscilloscope 33 , while the difference w_1-w_2 is a linear function of that amplitude; the zero value of w_1 and w_2 being one quarter their maximum value.

In view of the foregoing explanations of Figs. 2, 3, and 5 to 9, it will be understood by those skilled in the art that the bases 41 , 45 , 81 , 85 , 91 , and 95 , and the segments on line l and axis

16

$X-X$, respectively, represent different values of the horizontal extension, or width, of openings 21 , 22 , 71 , 72 , 90 , and 94 , respectively. Since, furthermore, the length of those bases and segments is equal to the right members of Equations 1, 2, and 4 to 9, for certain values of y , the width of the openings increases in proportion to the square of its distance from their respective tips V , W , V' , W' , V_1 , and W_1 . Moreover, the widths of any two paired openings increase at the same rate so that they are equal, although the openings are inversely positioned vertically. Pairs of openings which are thus positioned, and whose widths vary in the manner set forth above, have so far been shown and described only as employed in conjunction with the variable area recording optical system of Fig. 1. But the invention contemplates their employment also with certain variable density recording optical systems of the mirror oscilloscope type.

A variable density recording optical system in which a pair of openings according to the invention may advantageously be employed, is shown in Figs. 11 to 13 by way of example. Since this optical system is made up mostly of the same parts as that of Fig. 1, parts common to the two optical systems are designated by the same reference characters. It will thus be seen that the optical system of Figs. 11 to 13 differs from that of Fig. 1 only in that the microscope objective 14 and the spherical lens 15 of the latter optical system have been replaced in the former optical system by a cylindrical lens 114 whose cylinder axis is horizontal, and a pair of beam splitting spherical lenses 115 and 116 , respectively. A front elevation of lenses 115 and 116 is shown in Fig. 14.

Cylindrical lens 114 forms, by its action in the vertical plane, at recording point 139 an image of the two horizontal lines of light appearing at slit 27 , while spherical lenses 115 and 116 form, by their action in the horizontal plane, at the same position two distinct images of mirror 12 . There thus are produced at recording point 139 two horizontal lines of light in juxtaposition. The length of these two lines of light is constant, but their intensity may continuously be varied in accordance with the amplitude of the electrical impulses applied to oscilloscope 33 . Since, in all other respects, the optical system of Figs. 11 to 13 operates in the same manner as the variable density recording optical system shown in Figs. 1 to 3 of my U. S. Patent No. 2,312,259, granted Feb. 23, 1943, reference is made to that specification by way of further explanation.

When, therefore, as shown by way of example in Fig. 11, openings 21 and 22 are employed in the screen 20 of the optical system of Figs. 11 to 13, the intensity of each of the two horizontal lines of light at recording point 139 varies in proportion to the square of the amplitude of the electrical impulses applied to oscilloscope 33 , while the difference in intensity of the two lines of light is a linear function thereof. As film 31 moves vertically past recording point 139 , there is thus produced thereon a photographic record of the electrical impulses applied to oscilloscope 33 , which record consists of the two variable density tracks 135 and 136 in juxtaposition. Since the variation in intensity of the two lines of light at recording point 139 is continuous, each track 135 and 136 is a complete record of the electrical impulses. On account of the inverted position of openings 21 and 22 , however, track 136 is displaced 180° out of phase in rela-

tion to track 135 transversely of film 31 so that tracks 135 and 136 are the component half-tracks of a push-pull class A variable density track 137.

The methods of producing the variable density track 137 and the variable area track 37 thus both involve the following steps: Two horizontal lines of light are produced in juxtaposition at recording points 30 and 130, respectively. The amount of light flux contained in each line of light is continuously varied in proportion to the square of the amplitude of the electrical impulses applied to oscillograph 33, but the one amount of light flux is varied 180° out of phase in relation to the other amount of light flux. The variation of the two amounts of light flux is accomplished by varying either the length of the two lines of light, or their intensity. Track 37 is obtained in the first case, and track 137 in the second case.

It is well known in the art that any kind of sensitive emulsion with which film 31 may be coated, responds linearly not to its exposure, but to the logarithm thereof. The variation in density, therefore, of half-tracks 135 and 136 is not proportional to the square of the amplitude of the electrical impulses applied to oscillograph 33, although the variation in intensity of the two lines of light at recording point 130 is so proportional. But, for making a print of track 137 there may be employed methods, generally known to those skilled in the art, by which the complete photographic process is controlled so that the light transmission of the print is proportional to the exposure of film 31.

A print obtained in this manner is illustrated, by way of example, in Fig. 15. This figure shows, printed on film 51, a push-pull class A variable density track 152 which is composed of the two half-tracks 153 and 154 in juxtaposition. Like tracks 52 and 102, track 152 is assumed to be a record of the full cycle of a sine wave. This cycle is completely recorded on each half-track 153 and 154, but the two half-tracks are displaced 180° out of phase in relation to one another. That is to say, the region 155 of largest light transmission on half-track 153 is opposite the region 156 of smallest light transmission on half-track 154 transversely of film 51, and the region 157 of smallest light transmission on half-track 153 is, in the same sense, opposite the region 158 of largest light transmission on half-track 154.

Since track 152 was obtained by the photographic methods referred to above, its light transmission is proportional to the exposure of film 31 which, in its turn, is proportional to the intensity of the two lines of light at recording point 130. The light transmission of each half-track 153 and 154 hence varies in proportion to the square of the amplitude of the electrical impulses applied to oscillograph 33, while the difference in light transmission of half-tracks 153 and 154 is a linear function of that amplitude. Since, furthermore, the light transmissions of half-tracks 153 and 154 vary 180° out of phase in relation to one another, the light transmission of half-track 153 increases when that of half-track 154 decreases and vice versa.

Like tracks 52 and 102, track 152 may be reproduced with any conventional push-pull reproducing system, and the reproduction of the electrical impulses recorded thereon is undistorted for the reasons set forth hereinabove in connection with the description of track 52. Also, when those electrical impulses are sound currents, a reduction of ground noise is effected when sound is

reproduced from track 152. This reduction is due to the fact that, on account of the shape of openings 21 and 22, each half-track 153 and 154 has a light transmission whose zero value is one quarter its maximum value; the zero and maximum values of the light transmission of half-tracks 153 and 154 being its values for the rest position of mirror 12 and its maximum vibration, respectively.

The ground noise reduction obtained by the employment of openings 21 and 22 in the optical system of Figs. 11 to 13 amounts to 6 decibels. This result is sufficient to make the application of the electrical methods of ground noise reduction superfluous in a great number of practical cases. The production, therefore, of variable density sound tracks with ground noise reduction is materially facilitated by the present invention.

In the place of openings 21 and 22 there may be employed in the screen 20 of the optical system of Figs. 11 to 13 also the openings 21 and 72 of Fig. 5, the openings 22 and 71 of Fig. 6, the openings 71 and 72 of Fig. 7, or the openings 90 and 94 of Fig. 8. Substitution of any of the pairs of openings shown in Figs. 5 to 8 for openings 21 and 22, however, does not affect either the appearance, or the properties described hereinabove, of half-tracks 135 and 136, and 153 and 154, respectively. In all cases, there are produced at recording point 130 two horizontal lines of light of constant length whose intensity varies in proportion to the square of the amplitude of the electrical impulses applied to oscillograph 33.

In considering Fig. 15, finally, it should be borne in mind that the variation in light transmission of a variable density track can be illustrated only by differences in its shading, and that it is well-nigh impossible properly to indicate, in a shading made by hand, the particular variation in light transmission which half-tracks 153 and 154 have in accordance with the present invention. Actually, the variation in light transmission of half-tracks 153 and 154 is the exact counterpart of the variation in width of transparent portions 63 and 64 as diagrammatically illustrated in Fig. 4. Fig. 15 hence is merely a crude illustration of the push-pull class A variable density track 152.

In an actual embodiment of the optical systems of Figs. 1 and 11 to 13, the dimensions of the images on screen 24 may be different from those of the openings in screen 20. Such enlargement or reduction, which depends upon the ratio of imagery chosen for lens 23, does not affect the validity of the explanations made hereinabove, since it does not involve a change in proportion.

Tracks 52, 102, and 152, are shown in Figs. 4, 10, and 15, and have been described hereinabove, as printed from film 31 onto film 51. But these tracks may be produced also immediately on film 31 by adapting the optical systems of Figs. 1 and 11 to 13 for recording in accordance with the reversal method.

When the amplitude of the electrical impulses applied to the oscillograph 33 of the optical systems of Figs. 1 and 11 to 13 is very large, the images on screen 24 may be deflected to such a degree that their tips and bases cross slit 27. This effect of over-modulation interrupts the exposure of film 31. It may be avoided by combining the openings shown in Figs. 2 and 5 to 8 with an additional opening, or openings, of suitable shape in such a manner that the two or more openings form a single opening whose shape is again substantially triangular. This expedient, which in itself is well known in the art, is illustrated, by way of example, in Figs. 16 and 17 as applied to

openings 21 and 22, and openings 90 and 94, respectively.

Fig. 16 shows how, in order to obtain the desired result, opening 21 may be combined with the two rectangular openings 161 and 162, and opening 22 with the two rectangular openings 163 and 164, so as to form the substantially triangular openings 121 and 122, respectively. Openings 161 and 163 are equal, and so are openings 162 and 164. Openings 21, 161, and 162, are arranged so that one of the vertical edges of opening 161 coincides with the vertical edge 40 of opening 21. Since, however, this edge of opening 161 is longer than edge 40, its portion 165 extends beyond the tip V of opening 21. One of the horizontal edges of opening 162, on the other hand, coincides with the base 41 of opening 21 and the horizontal edge 166 of opening 161.

Correspondingly, openings 22, 163, and 164, are arranged so that one of the vertical edges of opening 163 coincides with the vertical edge 44 of opening 22. Since, however, this edge of opening 163 is longer than edge 44, its portion 167 extends beyond the tip W of opening 22. One of the horizontal edges of opening 164, on the other hand, coincides with the base 45 of opening 22 and the horizontal edge 168 of opening 163.

The transition from the parabolic edges 42 and 46 of openings 121 and 122, respectively, to their straight edges 165 and 167, respectively, is a smooth one because edges 165 and 167 are the tangents at the vertices of parabolic edges 42 and 46, respectively.

In Fig. 17, opening 90 is combined with openings 161 and 162, and opening 94 with openings 163 and 164, so as to form the substantially triangular openings 190 and 194, respectively. Openings 90, 161, and 162, are arranged so that opening 161 bisects opening 90. Opening 90 is thereby divided into the equal portions 99a and 99b with bases 91a and 91b and tips V₂ and V₃, respectively, and the portions 171 and 172 of the vertical edges of opening 161 extend beyond tips V₂ and V₃, respectively. Opening 162, on the other hand, has a horizontal edge which coincides with bases 91a and 91b, and the horizontal edge 166 of opening 161.

Correspondingly, openings 94, 163, and 164, are arranged so that opening 163 bisects opening 94. Opening 94 is thereby divided into the equal portions 94a and 94b with bases 95a and 95b and tips W₂ and W₃, respectively, and the portions 173 and 174 of the vertical edges of opening 163 extend beyond tips W₂ and W₃, respectively. Opening 164, on the other hand, has a horizontal edge which coincides with bases 95a and 95b, and the horizontal edge 168 of opening 163.

The transition from the parabolic edges 92 and 93, and 96 and 97, of openings 190 and 194, respectively, to their straight edges 171 and 172, and 173 and 174, respectively, is a smooth one because edges 171, 172, 173, and 174, are the tangents at the vertices of parabolic edges 92, 93, 96, and 97, respectively.

With openings such as openings 21 and 22, and 90 and 94, their total width is utilized for varying the two amounts of light flux passing through the slit 27 of the optical systems of Figs. 1 and 11 to 13. With openings such as openings 121 and 122, and 190 and 194, however, that part of their width which is equal to the horizontal extension, or width, of openings 161 and 163, respectively, does not effect a variation of the light flux since it is constant. The effective width of the latter openings hence is the difference between their

total width and the width of openings 161 and 163, respectively, so that it is equal to the total width of the former openings. The effective width of all openings thus is proportional to the square of its distance from their tips. But the total width of all openings increases in proportion to the square of its distance from their tips, no matter whether it is equal to, or larger than, their effective width. It is understood, of course, that in the cases illustrated in Figs. 16 and 17, the tips of the openings are rectangular rather than punctual as they are in the cases illustrated in Figs. 2 and 5 to 8.

It will thus be seen, when openings such as openings 121 and 122, and 190 and 194, are in the screen 20 of the optical systems of Figs. 1 and 11 to 13, the amount of light flux contained in each of the two horizontal lines of light at recording points 30 and 130, respectively, is continuously varied again in proportion to the square of the amplitude of the electrical impulses applied to oscilloscope 33. In case such openings are employed with the optical system of Fig. 1, therefore, the push-pull class A tracks recorded on film 31, and the prints made of these tracks on film 51, are composed of two variable area half-tracks, and each half-track has a modulated portion whose width varies again in proportion to the square of that amplitude. However, since a part of the width of the openings here under discussion is constant, a part of the width of this modulated portion is constant, too. The modulated portion hence has now an effective width which is equal to its total width less the constant part thereof. This effective width is proportional to the square of the amplitude referred to above and its zero value is one-quarter its maximum value, as in the case of the modulated portion of half-tracks 35 and 36, 53 and 54, and 103 and 104, whose effective width is equal to its total width.

In case openings such as openings 121 and 122, and 190 and 194, are employed with the optical system of Figs. 11 to 13 and prints are made on film 51 of the push-pull class A tracks recorded on film 31, and in accordance with the photographic methods mentioned hereinabove, the prints are composed of two variable density half-tracks, and each half-track has a light transmission which varies again in proportion to the square of the amplitude of the electrical impulses applied to oscilloscope 33. However, since a part of the width of the above openings is constant, a part of this light transmission is constant, too. The variable density half-tracks hence have now an effective light transmission which is equal to their total light transmission less its constant part. This effective light transmission is proportional to the square of the amplitude referred to above, and its zero value is one-quarter its maximum value, as in the case of half-tracks 153 and 154 whose effective light transmission is equal to their total light transmission.

Having thus described several embodiments of my invention, I wish to point out that it is not limited to the specific structures shown, but is of the scope of the appended claims.

What I claim is:

1. The method of producing on a film a photographic record of electrical impulses which includes moving said film past a recording point in a substantially vertical direction; producing at said recording point two horizontal lines of light in juxtaposition, each of said two lines of light containing a variable amount of light flux;

and continuously varying said amount in proportion to the square of the amplitude of said electrical impulses, but varying the amount of light flux contained in the one of said two lines of light 180° out of phase in relation to the amount of light flux contained in the other line of light.

2. The method of producing on a film a photographic record of electrical impulses which includes moving said film past a recording point in a substantially vertical direction; producing at said recording point two horizontal lines of light in juxtaposition, each of said two lines of light being of variable length; and continuously varying said length in proportion to the square of the amplitude of said electrical impulses, but varying the length of the one of said two lines of light 180° out of phase in relation to the length of the other line of light.

3. A photographic push-pull class A track on a film; said track being a record of electrical impulses, and composed of two variable area half-tracks displaced 180° out of phase in relation to one another transversely of said film; and each of said half-tracks being a complete record of said electrical impulses, and having a modulated portion whose width varies in proportion to the square of the amplitude of said electrical impulses.

4. A push-pull class A track according to claim 3 and in which said modulated portion is opaque.

5. A push-pull class A track according to claim 3 and in which said modulated portion is transparent.

6. A photographic push-pull class A track on a film; said track being a record of electrical impulses, and composed of two variable area half-tracks displaced 180° out of phase in relation to one another transversely of said film; and each of said half-tracks being a complete record of said electrical impulses and having a modulated portion whose effective width is proportional to the square of the amplitude of said electrical impulses, the zero value of said width being one quarter its maximum value.

7. The method of producing on a film a photographic record of electrical impulses which includes moving said film past a recording point in a substantially vertical direction; producing at said recording point two horizontal lines of light in juxtaposition, each of said two lines of light being of variable intensity; and continuously varying said intensity in proportion to the square of the amplitude of said electrical impulses, but varying the intensity of the one of said two lines of light 180° out of phase in relation to the intensity of the other line of light.

8. A photographic push-pull class A track on a film; said track being a record of electrical impulses, and composed of two variable density half-tracks displaced 180° out of phase in relation to one another transversely of said film; and each of said half-tracks being a complete record of said electrical impulses, and having a light transmission which varies in proportion to the square of the amplitude of said electrical impulses.

9. A photographic push-pull class A track on a film; said track being a record of electrical impulses, and composed of two variable density half-tracks displaced 180° out of phase in relation to one another transversely of said film; and each

of said half-tracks being a complete record of said electrical impulses and having an effective light transmission which is proportional to the square of the amplitude of said electrical impulses, the zero value of said light transmission being one quarter its maximum value.

10. A photographic push-pull class A track on a film, said track being a record of electrical impulses, and composed of two half-tracks displaced 180° out of phase in relation to one another transversely of said film; and each of said half-tracks being a complete record of said electrical impulses, and having a light transmission which varies in proportion to the square of the amplitude of said electrical impulses.

11. In an optical system, a screen having two openings which are substantially triangular and alike; each of said two openings having a tip, and a horizontal extension which increases in proportion to the square of its distance from said tip; and said two openings being spaced apart horizontally and inversely positioned vertically.

12. In an optical system, a screen having two openings which are substantially triangular and alike; each of said two openings having a tip, and an effective horizontal extension which is proportional to the square of its distance from said tip; and said two openings being spaced apart horizontally and inversely positioned vertically.

13. In an optical system, a screen having a first opening and a second opening, said first and second openings being substantially triangular and alike; said first opening having a first tip, and a first horizontal extension which increases in proportion to the square of its distance from said first tip; said second opening having a second tip, and a second horizontal extension which increases in proportion to the square of its distance from said second tip; said first and second horizontal extensions increasing at the same rate; and said first and second openings being spaced apart horizontally and inversely positioned vertically.

14. In an optical system, a screen having a first opening and a second opening, said first and second openings being substantially triangular and alike; said first opening having a first tip, and a first effective horizontal extension which is proportional to the square of its distance from said first tip; said second opening having a second tip, and a second effective horizontal extension which is proportional to the square of its distance from said second tip; said first and second horizontal extensions being equal; and said first and second openings being spaced apart horizontally and inversely positioned vertically.

15. In an optical system, a screen having a first opening and a second opening; said first opening having a first tip, a first base, and a first width which increases in proportion to the square of its distance from said first tip; said second opening having a second tip, a second base, and a second width which increases in proportion to the square of its distance from said second tip; said first and second widths increasing at the same rate; said first and second bases being equal; said first tip being in alignment with said second base; and said second tip being in alignment with said first base.

JOHN A. MAURER, JR.
